FISH LURE

Joseph J. Sabol, West Hazleton, Pa., assignor of fractional part interest to Joseph J. Ustynoski, West Hazleton, Pa.

Filed Jan. 28, 1970, Ser. No. 21,122

Term of patent 14 years

Int. Cl. D22—07

U.S. Cl. D22—27

FIG. 1 is a top plan view of a fish lure showing my new design.

FIG. 2 is a bottom plan view thereof.

FIG. 3 is a top plan view thereof with the legs extended as occurs when the lure is pulled rapidly through the water.

FIG. 4 is a side elevational view thereof.

FIG. 5 is a rear end view thereof.

FIG. 6 is a front end view thereof.

I claim:

The ornamental design for a fish lure, as shown.
